ADHESIVE APPLYING MECHANISM

Harry F. Affelder, Cleveland Heights, Ohio

Original application November 12, 1934, Serial No. 752,666. Divided and this application June 8, 1937, Serial No. 147,077

7 Claims. (Cl. 91—50)

This invention relates to adhesive applying mechanism and is a division of my prior application Serial No. 752,666, filed November 12, 1934, which has matured into Patent 2,083,539, issued on June 15, 1937.

The object of the invention is to provide an improved adhesive applying mechanism which is adaptable for use on machines for making various kinds of articles from paper or other flexible material, and is particularly useful in machines such as constitutes the subject matter of my prior application, above referred to wherein the adhesive applying mechanism is on a revolving head and receives adhesive from a stationary container or so called gum box.

The invention may be briefly summarized as consisting in certain novel details of construction, and combination and arrangement of parts which will be described in the specification and set forth in the appended claims.

In the accompanying drawings I have shown my invention applying to a machine which, as more fully described in my prior application, above referred to, is utilized for making bottle collars and like articles from strips of flexible material, such as paper, which are adapted to be rolled up onto a former and to have their overlapping ends united by the application of adhesive and by punching tabs in the overlapping ends.

In the drawings, Fig. 1 is a side elevation of the upper part of the machine, or of so much thereof as is pertinent to the present invention;

Fig. 2 is a horizontal sectional view substantially along the line 2—2 of Fig. 1, omitting some parts unessential to the invention;

Fig. 3 is an enlarged fragmentary view showing the adhesive applying mechanism detached from associated parts;

Fig. 4 is a sectional view substantially along the line 4—4 of Fig. 1, showing particularly the gum box for supplying the adhesive which is applied to one end of each strip before it is formed into the article in question; and

Fig. 5 is a sectional view taken substantially along the line 5—5 of Fig. 3, showing another detail of the adhesive applying mechanism.

Referring now to the drawings, the machine has a horizontal frame or table 20 which is supported from the floor by legs not shown. At one side of the bed is an upstanding standard 22 supporting a motor 23 which, through reduction gearing 24, drives a vertical centrally disposed shaft 25 supported in bearings located in the

boss 26 of an arm 26a extending inwardly from the standard 22. The shaft has at the top a bevel gear 24a which forms a part of the reduction gearing 24 and will be referred to later.

Secured to the lower end of the shaft 25 so as to rotate therewith is an arm 27 on the lower free end of which is a block 28 supporting a diagonally disposed shaft on which is journaled a frusto-conical former 30 which extends inwardly with respect to the frame or table 20 with its axis inclined downwardly and intersecting the vertical axis of the machine. At the larger end of the former 30 is a bevel pinion 31 which engages a bevel ring gear 32 supported in fixed position on the frame 20. Consequently, as the shaft 25 and the arm 27 are rotated, the bevel pinion 31 is caused to roll around the ring gear 32, with the result that the former 30 revolves about the vertical axis of the machine and rotates on its own axis.

On each revolution of the former, there is adapted to be wrapped around its conical surface a strip of paper or the like from which one of the articles is to be produced, with the ends of the strip overlapping. While the former here shown is of frusto-conical shape, the particular shape will depend upon the shape of the article to be produced. That is to say, the former will have a frusto-conical shape when the article produced is frusto-conical. On the other hand, if the articles to be produced on the machine are conical, cylindrical, or otherwise shaped, of course the former will be similarly shaped.

During each cycle of the revolving and rotating movements of the former 30, the latter picks up and causes to be wrapped around its frusto-conical surface, as stated above, one of the strips, designated 34 in Fig. 2. For this purpose I arrange beneath and just inside the ring gear 32 an elevator on which is adapted to be placed a stack of the strips 34 (see Fig. 2), the arrangement being such that the former rolls over and picks up the uppermost strip of the stack during each cycle.

The mechanism by which the elevator is caused to automatically move upwardly, to keep the uppermost strip of the stack at the right height relative to the former 30, forms no part of the present invention and is neither shown nor described, but for a complete understanding of this mechanism which may be employed for this purpose reference may be had to my prior application referred to.

Suction means is preferably utilized to cause the strip to be firmly held to and wrapped around

the former 30 and as the suction means forms no part of the present invention some of the details of the same are not herein illustrated, but are shown in my prior application. It will be sufficient to here state that I provide for this purpose a suction tube 45, one end of which is attached to the block 28 forming a part of the rotating arm 27, this end of the tube being adapted to be connected by suitable passage-ways to air ports which extend from the periphery or outer surface of the former 30 inwardly to a passageway suitably connected with the said end of the tube 45. The other end of the tube 45 is connected to an opening extending 10 axially through the central vertical shaft 25 and in the upper end of the opening, through the shaft 25, is seated a fitting to which is connected a suction tube 47 leading to a vacuum pump, not shown. A vacuum gauge 48 at the top of the 15 fitting is preferably provided, and an adjusting screw 49 is screwed into a passageway leading to the central passageway of the fitting, so that the degree of vacuum exerted in the suction line may be varied as desired. The fitting has 20 a close fit in the top of the shaft 25 but does not rotate with the shaft as the stiffness of the tube 47 is sufficient to hold it against rotation.

Thus, as the rotating and revolving former 30 rolls over the uppermost strip of the stack, the 25 suction exerted on the uppermost strip which the roll engages causes the strip to be wrapped closely about the former and the suction continues to be exerted on the strip until its ends are securely fastened together in a manner to 30 be explained, and after the ends are fastened together the suction is relieved so that the completed article may be stripped from the former. A means for accomplishing this is fully disclosed in my prior application.

40 Before the former 30 rolls up onto the surface of the uppermost strip 34 of the stack which is supported on the platform, a small quantity of adhesive is deposited on the end of the strip remote from that which the rotating and revolving former first engages, so that when the strip is completely rolled on the former the overlapping ends will be held together by the adhesive. To apply the adhesive to the end portion of the strip before it is picked up, the following mechanism is utilized:

50 Mounted in stationary position above the rotating arm 27 on a frame 56 secured to the inwardly projecting arm 26a of the standard 22 is a gum box 57 (Figs. 1 and 4) in the sides 55 of which is journaled a small shaft carrying a gum roller 58, the surface of which is adapted to contact with the gum in the box, as will be apparent from Fig. 4. On one end of the shaft carrying the gum roller 58 is a star wheel 59. 60 During each revolution of the arm 27, adhesive is transferred from the periphery of the roller 58 onto the surface of a rotating and revolving roller 60 (Figs. 1 and 5) preferably on a yieldable part of the periphery of the roller 60, and in 65 this instance on the arc-shaped surface of a yieldable dog 61 pivoted in a slot in the roller 60, the free end being pressed out by a spring surrounding an adjustable retaining screw 62, as clearly indicated in Fig. 5. By having the 70 adhesive transferred from the surface of the roller 58 onto a yieldable member at the periphery of the roller 60, the necessity for fine adjustment is done away with.

75 This roller 60 is fixed to a short horizontal shaft 63 which projects from the inner end of

and is in line with the rotating arm 27. This shaft 63 has its inner end journaled in the adjacent end of arm 27 and its outer end is supported and journaled in a bracket 64 which in turn is supported by a frame 65 secured to and projecting from the arm 27, as clearly shown in Fig. 1. Also fixed to rotate with the shaft 63 is a spur gear 66 and a bevel gear 67, the latter engaging a stationary bevel gear 68 fixed to the lower inner part of the arm 26a concentric with respect to the shaft 25. By reason of this arrangement, the roller 60 revolves around the axis of the main vertical shaft 25 and it rotates with its supporting shaft 63, and each time that it passes the lower surface of the roller 58, a 15 film of adhesive is applied to the arc-shaped surface of the dog 61.

From the surface of the dog 61 the adhesive is transferred to yieldable fingers 69 (see Figs. 1 and 5) at the free end of a rotating and revolving arm 70 which is fixed to a short horizontal shaft 71 journaled in the lower end of the revolving bracket 64 which, as previously stated, is supported by the frame 65 secured to the revolving arm 27. Also fixed to this short shaft 25 71 is a pinion 72 which engages the spur gear 66 on the upper horizontal shaft 63. By reason of this arrangement, the applying fingers 69 are carried around with the revolving arm 27 and they rotate about the axis of shaft 71. As they 30 are passing through the upper arc of the circle in which they rotate, they pick up adhesive from the surface of the dog 61, and when they are rotating through the lower part of the circle they touch and transfer the adhesive onto the 35 end portion of the uppermost strip 34.

In this instance, the pinion 72, because of lack of space, is made one-half the size of the gear 66, in which event the fingers 69 rotate twice 40 while the upper roller carrying the dog 61 makes one rotation, but that is immaterial since it simply means that the adhesive applying fingers 69 rotate twice about the axis of the shaft 71 while they revolve once about the vertical axis of the machine, and therefore make one idle stroke 45 and then an adhesive applying stroke, etc. That is to say, at each alternate rotation the fingers apply adhesive to the uppermost strip 34.

The roller 58 which projects into the gum box 57 is preferably turned at each revolution of the 50 revolving arm 27 so that there will always be plenty of adhesive on the lower part of the periphery of the roller, and for this purpose I provide at the top and outer portion of the bracket 64 a roller 73 (see Fig. 1) which on each revolution 55 of the arm 27 strikes one of the teeth of the star wheel 59 and rotates it and the gum roller 58 a predetermined amount. To limit the rotative movement given to the star wheel and therefore to the gum roller 58, a stop pin 74 is arranged so 60 that its lower end projects into the path of the upper tooth of the star wheel. This pin, which is spring-pressed downwardly, is movably supported in a strap 75 secured to a frame 76 projecting laterally from the upper part of the boss 65 26 supporting the main vertical shaft 25 (see Fig. 1). At the top of the pin 74 is a roller 77 which rides on the upper surface of the large bevel gear 24a which is secured to the top of the vertical shaft 25 and on the top of this bevel gear 24a 70 is a cam or boss 78 which at each revolution of the gear 24a momentarily lifts the roller 77 and therefore the pin 74 just before the roller 73 engages the lowermost tooth of the star wheel so as to allow the star wheel to be turned through an 75

arc equivalent to the distance between two adjoining teeth and not more than that distance, the lower end of the pin 74 being released and moving down into the path of the tooth next to the one which it had previously engaged so as to limit the movement of the star wheel and therefore of the gum roller 58 to the amount desired.

I do not regard it essential that the adhesive be applied precisely as here shown, that is, to the end of the strip remote from the one which is first rolled onto the former, for it may be applied onto the other end of the strip when the strip is partly rolled onto the former.

Furthermore, I do not regard it essential that the gum roller be turned by the specific mechanism herein illustrated, i. e. through the medium of the star wheel 59 and of the roller or equivalent means which revolves with the head. Obviously, a pawl and ratchet mechanism operated from a cam or other means on the rotating bevel gear 24a could be employed.

In some instances, as, for example, with a machine such as utilized for forming bottle collars, it is desirable, in order that the machine have a high production rate, that the holding action of the adhesive between the overlapping ends of the article be supplemented by tabs punched in the overlapping ends, which tabs serve the important purpose of holding the ends together until the adhesive has dried. For this purpose there is provided a flat punch plate 79 in fixed position just inside the ring gear 32 at a height such that the former 30 will roll over it and at the desired point circumferentially of the ring gear with reference to the stack of strips 34, this punch plate being in this instance supported by a bracket secured to the bed 20, as clearly shown in Fig. 2. This punch plate carries a series of punches 80 corresponding in number and arrangement to the number and arrangement of the tabs which are to be punched in the overlapping ends of the strip which is wrapped around the former 30. Likewise, there is provided on the conical surface of the former 30 a die plate 81 (which forms a part of the conical surface), this die plate having a series of dies or openings 82 corresponding in number and arrangement to the series of punches 80, the whole being so arranged that at each revolution of the former 30 the die plate 81 rolls over the punch plate 79 so that the protruding ends of the punches will enter the die openings. The overlapping ends of the strip 34 which is wrapped around the former 30 cover the die openings 82 of the die plate 81 so that, as the revolving and rotating former 30 rolls over the punch plate, tabs are punched inwardly in the overlapped ends of the strip, thus locking the ends of the strip together and completing the formation of the article.

In stating that the former 30 rolls over the punch plate, the word "over" is used in a broad sense, meaning that there is a relative rolling action between the former and the punch plate. For example, the punch plate may be supported at the proper level above the bed so that the former will roll along its surface beneath the same.

As soon as the former 30 passes the punch plate, the article, which is now completed, is stripped off the former at its smaller or inner end, and in this instance slides down into or onto any suitable receiving member. The stripping of the articles from the former 30 is preferably accomplished by a suitable stripper wheel 84

which is rotatably supported on the frame or bed 20 inside the ring gear close to the punch plate 79, as clearly indicated in Fig. 2, so that as the former 30 passes the punch plate the collar or other article thereon comes in contact with the periphery of the stripper wheel which may be formed of rubber, such as sponge rubber, and causes the article to be slid off the former 30 onto or into the receiving member. It will be remembered that the suction which causes the strip to be picked up and held on the former is automatically relieved just before the stripper wheel engages the formed article to remove it from the former 30. In this instance the stripper wheel is mounted on a shaft 85 provided at its outer end with a sheave 86 engaged by a driven belt 81 (Figs. 1 and 2) passing around a second sheave 88 at the outer end of an upper horizontal shaft 89 supported on the frame 16 and provided at its inner end with a bevel pinion which engages and is rotated by the horizontal bevel gear 24a at the top of the machine.

In this instance the articles when stripped from the former 30 pass down a gooseneck 90, which forms a continuation of the non-rotating shaft 25 about which the former 30 rotates, this gooseneck being a pipe or rod having a vertical portion which extends down beneath the bed 20 in line with the axis of the machine and, therefore, in line with the axis of revolution of the forming 30 head. Supported at a suitable distance beneath the bed is a turntable 92 adapted to be turned or indexed in a horizontal plane and projecting up from this turntable is a series of receiving pins 93 which are adapted to receive the articles as 35 they slide down off the lower end of the gooseneck.

The formed articles may be received, however, in or on receiving members other than those herein referred to, the details of receiving members and of the indexing mechanism therefor, not being material to the present invention.

Above, I have described with considerable detail the adhesive applying mechanism constituting the subject matter of the present invention 45 and I have, more briefly, referred to some associated parts which perform important functions in a particular type of machine, in this instance, a collar forming machine, but I wish it understood that I do not intend to limit the application of the adhesive applying mechanism to a machine of this particular character, as it may have utility in other types of machines wherein articles are formed into suitable shape, from paper or other flexible material, and whose ends 50 are to be secured together by the application of adhesive to a suitable part of the strip, whether or not the holding action of the adhesive is supplemented by other holding means, such as by tabs punched in the overlapping ends.

I therefore do not desire to be confined to any particular kind of machine in which the adhesive applying mechanism may be embodied or to a machine for forming any particular kind of an article. Furthermore, I do not desire to be confined to the precise details of the adhesive applying mechanism herein shown, but aim in my claims to cover all modifications which do not involve a departure from the spirit and scope of the invention.

Having thus described my invention, I claim:

1. In a machine of the character described, a member adapted to support a strip of flexible material, an arm revolving relative to said member, a stationary gum fountain, gum transferring

- means carried by the arm arranged to take a charge of gum from the fountain as it moves past the fountain, and an applicator also carried by the arm arranged to receive a charge of gum from the transferring means during the same revolution of the arm and to deposit said charge upon said strip as the applicator moves past the strip.
2. In a machine of the character described a member adapted to support a strip of material on which adhesive is adapted to be applied, a revolving head, a stationary gum fountain, a gum transferring member carried by the head and arranged to take a charge of gum from the fountain as it moves past the same, an applicator also carried by the head and arranged to receive a charge of gum from the transferring member during the same revolution of the head and to deposit said charge upon said strip as the applicator moves past the strip, and means for rotating the transfer member and applicator on the head.
3. In a machine of the character described a work supporting member, a head revolving relative to said member, a stationary gum fountain, a pair of shafts carried by said head, means for rotating the shafts, a transfer member on one shaft arranged to take a charge of gum from the fountain as it moves past the fountain, and an applicator on the other shaft arranged to receive a charge of gum from the transfer member and to deposit said charge upon the strip as the applicator moves past the strip.
4. In a machine of the character described, a work supporting member, a vertical shaft, a revolving arm carried by said shaft, a pair of shafts carried by said arm, gearing means for rotating said pair of shafts in opposite directions as they revolve, a transfer member on one of said pair of shafts, an applicator on the other of said pair of shafts adapted to engage said transfer member, a gum fountain supported on the frame of the machine, and a gum roller arranged to take gum from said fountain, said transfer member being arranged to contact said gum roller once during each revolution of the arm.
5. In a machine of the character described, a frame, a work supporting member thereon, a bracket carried by the frame above said supporting member, a vertical shaft mounted in the bracket, means for rotating said shaft, an arm carried by said shaft revolving with the shaft above said work supporting member, a pair of shafts carried by said arm, a gum fountain mounted on the bracket, a gum roller arranged to take gum from said fountain, gearing means actuated by the rotation of said vertical shaft for rotating said gum roller at one point in the revolution of said arm.
6. In a machine of the character described, a frame, a work supporting member thereon, a bracket carried by the frame above said supporting member, a vertical shaft mounted in the bracket, means for rotating said shaft, an arm carried by said shaft and adapted to revolve with the shaft above said work supporting member, a pair of vertically spaced horizontal shafts carried by said arm, a gum fountain mounted on the bracket, a gum roller arranged to take gum from said fountain, gearing means actuated by the rotation of said vertical shaft for rotating said horizontal shafts as they revolve about the vertical shaft, a gum transfer member on the upper horizontal shaft, a gum applicator on the lower horizontal shaft, said applicator being adapted to contact said transfer member when the applicator is in its uppermost position and to contact work on the work supporting member when the applicator is in its lowermost position, and said transfer member being adapted to engage said gum roller at one point in the revolution of said arm.
7. In a machine of the character described, a support adapted to receive an article to which gum is to be applied, a stationary gum fountain, and a gum transferring and applying mechanism movable with respect to the fountain, said mechanism including a member arranged to take a charge of gum from the fountain as the said mechanism moves past the fountain, and a second member arranged to receive the charge of gum from the first member and to deposit the charge upon the article.

HARRY F. AFFELDER.
